UNITED STATES PATENT OFFICE.

CHARLES L. DUNHAM, OF SISTERSVILLE, WEST VIRGINIA.

PIPE-WRENCH.

1,072,320.

Specification of Letters Patent.

Patented Sept. 2, 1913.

Application filed May 1, 1913. Serial No. 764,857.

To all whom it may concern:

Be it known that I, CHARLES L. DUNHAM, a citizen of the United States of America, residing at Sistersville, in the county of 5 Tyler and State of West Virginia, have invented certain new and useful Improvements in Pipe-Wrenches, of which the following is a specification, reference being had therein to the accompanying drawing.

10 This invention relates to pipe wrenches and more particularly to that type disclosed in Patents Number 656,154 and Number 818,877, granted August 14, 1900 and April 24, 1906 respectively.

15 Besides having the same objects in view as disclosed in the above entitled patents, the present invention aims to provide the lever or handle of the wrench with a novel pivot pin for holding a large link section 20 in engagement therewith, the construction of the pivot pin being such that considerable leverage and power can be obtained when operating the wrench without subjecting the pivot pin to such stresses and strains 25 that would tend to snap the same or fracture the pivot end of the lever or handle.

My invention further aims to provide a gripping link of a pipe wrench with a reversible gripping member that presents a 30 sharp gripping edge for engaging a pipe or cylindrical structure upon which the wrench is used. The gripping member can be adjusted whereby four gripping edges can be used before the member is discarded and in 35 some instances all the links of the wrench of the above type can be provided with the members.

My invention further aims to accomplish the above results by a mechanical construction 40 consisting of comparatively few parts that are easy to assemble, inexpensive to manufacture and highly efficient for the purposes for which they are intended.

The invention will be hereinafter specifically described and then claimed and reference will now be had to the drawing, 45 wherein:—

Figure 1 is a side elevation of a portion of the wrench, Fig. 2 is a transverse sectional view of the same, and Fig. 3 is a front elevation of a portion of the wrench.

Further describing my invention in detail with reference to the accompanying drawing, wherein like numerals denote corresponding parts throughout: 1 denotes a por-

tion of a handle or lever that has the outer end thereof provided with an irregularly shaped head 2, said head being substantially oval in elevation and presenting a curved binding surface 3. The head is provided 60 with a crescent-shaped opening 4 and one of the walls of said opening provides a lug 5, while the opposite wall 6 of said opening presents a shoulder 7.

The reference numeral 8 denotes an enlarged link section and 9 and 10 intermediate link sections that are pivotally connected to the enlarged link section 8 by pins 11. The enlarged link section 8 has the inner end thereof bifurcated, as at 12 to 65 receive the head 2 of the handle or lever 1, and the bifurcated end of the enlarged link section 8 is provided with a transverse pivot pin 13. The pin in cross section is substantially rectangular except for one edge thereof, which is rounded, as at 14 to conform to the curvature of the wall 6 of the opening 4. I attach considerable importance to the shape of this pivot pin insomuch that it is firmly held by the enlarged link section 8 70 and when passing through the opening 4 it presents a flat surface 15 that can be engaged by the shoulder 7 of the head 2 and a flat surface 16 against which the lug 5 75 rides when the wrench is tightened upon a 80 pipe.

Pivotally connected to the link section 10 by a pin 17 is a grasping-link or jaw 18 adapted to extend into the enlarged link section 8 whereby it can be engaged by the 90 binding surface 3 of the head 2. To permit of this, the edge of the link or jaw 18 has three seats 19, 20 and 21 that permit of cylindrical structures of various diameters 95 being gripped by the wrench. As an instance, the seats 19 and 20 can be used for caps and collars and the seat 21 for a pipe that receives the caps and collars, it being understood that the pipe is held by a wrench or other device while the cap or collar is 100 screwed upon the same by another wrench.

The intermediate link section 9 is provided with a transverse substantially rectangular groove 22 and detachably mounted in said groove is a substantially rectangular gripping member 23. The sides of the member 23 are in parallelism but the front and rear sides thereof are beveled in opposite directions, whereby the member will have four gripping edges and by changing the position 105 110

of said member either of the edges can be used. When one edge is worn the member can be reversed and in this manner the longevity of said members is considerably increased.

To understand the operation of the wrench it might be well to consider that the pivot pin 13 held by the bifurcated end of the enlarged link section 8 is stationary. 10 By shifting the lever or handle 1 the curvature of the wall 6 riding against the rounded edge 14 of the pivot pin shifts the lug 5 into engagement with the flat surface 16 of said pin, and the further movement of the 15 handle or lever causes the lug to ride or, as it were, to roll upon the flat surface. While this is accomplished the binding surface 3 of the head 2 is brought into engagement with the seat 19 and as the handle or lever 20 is moved the grasping-link or jaw is shifted into engagement with the pipe upon which the wrench is placed, pressing the pipe against the intermediate links whereby the 25 gripping member 23 will bite into the surface of the pipe. As the handle or lever is further shifted there is further riding or rolling action of the lug upon the flat surface 16 of the pivot pin and it is this action that tightens the link sections of the wrench, 30 prevents the wrench from slipping and permits of considerable leverage being obtained without any danger of breaking the pivot pin. The very shape of the pin is such that stresses and strains upon the same are distributed throughout the pin and the bifurcated end of the enlarged link section 8.

The shoulder 7 of the head 2 holds the handle or lever in an operable position relatively to the link section 8, whereby the 40 grasping link or jaw can be easily placed in position to be engaged by the head of the handle or lever. In some instances, the shoulder 7 engages the pivot pin and cooperates with the lug 5 in holding the head 45 2 in engagement with the grasping-link or jaw 18, and it is the peculiar shape of the opening 4 and the cross sectional area of the pivot pin that permits of a positive action when gripping a pipe and insures a 50 greater degree of safety and a minimum degree of wear upon the working parts of the wrench.

One embodiment of the invention has been illustrated, but it is to be understood that 55 the structural elements are susceptible to such variations and modifications as fall within the scope of the appended claims.

What I claim is:—

1. In a pipe wrench, a handle or lever having a head provided with a substantially 60 crescent-shaped opening, link sections, and a pivot pin carried by one of said sections and extending through said opening, said pivot pin being substantially rectangular and presenting a flat gripping surface 65 adapted to be engaged by one of the walls of said opening.

2. In a pipe wrench, a handle having a head provided with a substantially crescent-shaped opening, and a rectangular pivot pin 70 extending through said opening and engaged by some of the walls of said opening and adapted to connect link sections to said handle.

3. In a pipe wrench, a handle, links, a 75 pivot pin carried by one of said links and extending through an end of said handle, said pin being substantially rectangular in cross section, and a lug carried by said handle and adapted to ride upon one of the 80 flat surfaces of said pivot pin.

4. In a pipe wrench, a handle having a head provided with a crescent-shaped opening, a lug forming one of the walls of said opening, a shoulder presented by another 85 wall of said opening, pivoted link sections, and a pivot pin carried by one of said sections and extending through the opening of said head, said pivot pin being substantially 90 rectangular in cross section and presenting flat gripping surfaces adapted to be engaged by said shoulder and said lug.

5. In a pipe wrench, a handle having a head provided with a crescent-shaped opening having walls presenting a lug and a 95 shoulder, pivoted link sections, one of said sections having a bifurcated end to receive the head of said handle, a pivot pin carried by the bifurcated end of said section and extending through the opening of the head of 100 said handle, said pivot pin being substantially rectangular in cross section and presenting flat gripping surfaces adapted to be engaged by said shoulder and said lug, and a grasping jaw carried by said link sections and presenting seats adapted to be engaged by the head of said handle.

In testimony whereof I affix my signature in the presence of two witnesses,

CHARLES L. DUNHAM.
